UNITED STATES PATENT OFFICE.

MORRIS B. BREWSTER, OF CHICAGO, ILLINOIS.

AUTOMATIC CYLINDER-COCK.

1,361,004.

Specification of Letters Patent. Patented Dec. 7, 1920.

Application filed May 26, 1920. Serial No. 384,493.

To all whom it may concern:

Be it known that I, MORRIS B. BREWSTER, a citizen of the United States, residing at Chicago, county of Cook, State of Illinois, have invented a certain new and useful Improvement in Automatic Cylinder-Cocks for Locomotives, and declare the following to be a full, clear, and exact description of the same, such as will enable others skilled in the art to which it pertains to make and use the same, reference being had to the accompanying drawings, which form a part of this specification.

My invention has for its object to produce a simple and novel device which will automatically drain the water from locomotive cylinders without waste of steam, which will relieve against excessive pressure, and which may be controlled at will by the engineer.

Viewed in another of its aspects my invention may be said to have for its object to produce an automatic cylinder cock for locomotives which, while simple and compact, will afford a large discharge opening.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a side elevation of a fragment of an engine cylinder having my improved device attached thereto;

Fig. 2 is a top plan view of the device removed from the cylinder;

Fig. 3 is a section taken approximately on line 3—3 of Fig. 2; and

Fig. 4 is a section taken approximately on line 4—4 of Fig. 2 and illustrating a different position of the valve from that occupied by the corresponding valve in Fig. 3.

My improved device may be made in individual units, one for each end of a cylinder or, since two such devices will be required for each locomotive engine cylinder, each unit may be made to contain two devices, thus simplifying the manufacture and the work of attaching and connecting up the devices; the drawings illustrating this latter form of my invention.

Referring to the drawings, 1 represents a suitable casing or housing having therein

two cylindrical chambers, 2 and 3, arranged side by side with their axes vertical. In the bottom of the casing, below each of the cylindrical chambers is a large opening, 4, preferably only slightly smaller in diameter than the diameter of the chambers. Each of the openings is surrounded by a downwardly-facing valve seat, 5. The partition wall, 6, between the two chambers extends from the top to the bottom thereof; but the remainder, or a large part thereof, of each cylindrical wall, 7, terminates at some distance above the bottom wall, 8, of the housing or casing and, furthermore, is spaced apart from the side and end walls, 9 and 10, so as to leave a space or passage, 11, between the same. Each of the spaces, 11, is placed in communication with an end of a locomotive cylinder, such as indicated at 12, through a suitable pipe connection, 13, screwed into or otherwise connected to the corresponding end wall, 10, of the casing or housing. The pipes, 13, are made of large diameter so as to permit a free flow of water out of the engine cylinders, this water entering the spaces or chambers, 11, and, when free to do so, flowing quickly out through the discharge openings, 4.

In each of the cylindrical chambers is a hollow piston or short plunger, 14, whose length is preferably no greater than the height of the cylindrical walls, 7. Lying below each piston or plunger is a valve, 15, adapted to seat upwardly against the corresponding valve seat, 5. Each valve has a stem, 16, extending upwardly through the piston and having on its upper end a collar or flange, 17, which rests upon a strong spring, 18, housed within the hollow cylinder. The stem of the valve, where it joins the valve proper, is gradually enlarged as indicated at 19 and co-operates with a correspondingly-shaped opening, 20, in the bottom of the piston to form a water-tight and steam-tight joint when the valve is drawn upwardly by the spring 18 until the part 19 engages the seat 20. The spring 18 is placed under initial tension somewhat greater than maximum boiler pressure.

Normally, when there is no pressure in the engine cylinder, both valves take the position occupied by the left hand valve in Fig. 3; each piston and its valve having descended as a unit, under the action of

gravity, so as to open the corresponding discharge port. Any water in either end of the engine cylinder may therefore flow freely out of the draining device. As soon as steam is introduced into one end of the engine cylinder, for example the right hand end in Fig. 1, and flows through the corresponding pipe into the drainage device, it exerts a downward pressure on the upper 10 face of the corresponding valve 15 and upwardly on the bottom face of the corresponding piston, 14. The parts are so proportioned that the effective piston area exposed to the action of the steam is greater 15 than the effective area of the valve which is similarly exposed, and therefore the resulting differential pressure raises the piston and valve bodily into the position illustrated on the right hand side in Fig. 3; closing the 20 outlet port and preventing the escape of steam. While the piston in the engine cylinder moves ahead, the left hand drain valve remains open and it does not close until steam is admitted into the left hand end of 25 the engine cylinder; whereupon it will be closed by the differential action of the steam as heretofore explained. As soon as the right hand end of the engine cylinder is open to exhaust, the right hand drain valve 30 opens and permits water of condensation to escape.

If, for any reason, there should be an abnormally high pressure in either end of the engine cylinder such, for example, as might 35 occur in case water were trapped in one end of the cylinder, this excess pressure, acting downwardly on the exposed surface of the corresponding drain valve, would overcome the tension of the spring and force the valve down as indicated in Fig. 4; thus opening 40 the discharge port and relieving the pressure in the engine cylinder before injury can result therefrom.

In order to permit the engineer to open 45 the valves of the draining device at will, I have provided an air-pipe, 21, into which the engineer may cause air under pressure to be admitted, the pipe, 21, having branches, 22 and 23, connected to inlet ports, 50 24 and 25, leading through one of the side walls of the casing, 1, from the upper ends of the cylindrical chambers 2 and 3 respectively. By this means air under pressure may be introduced into the upper end 55 of each of the cylindrical chambers, causing the pistons therein, and their associated valves, to be forced downwardly.

I claim:

1. A housing having an outlet in the bottom 60 thereof and an inlet, a downwardly-opening valve for said outlet, a piston mounted in said housing and adapted to be moved upwardly by pressure in the latter, and a yieldable connection between said 65 valve and said piston constructed and ar-

ranged to permit them to move away from each other when forces of predetermined strength are applied thereto.

2. A housing having an outlet in the bottom thereof and an inlet, said housing having therein above said outlet an open-bottom chamber of larger cross sectional area than said outlet, a piston fitting slidably in said chamber, a downwardly-opening valve for said outlet, said valve having a surface 75 exposed to pressure in the chamber of smaller area than the area of said piston and a connection between said valve and said piston.

3. A housing having an inlet and an outlet, there being in the housing a cylindrical chamber open on the side toward said outlet and of larger cross sectional area than the outlet, a piston slidably mounted in said chamber, an outwardly-opening valve for said outlet, said valve having a surface exposed to pressure in the chamber of smaller area than the area of said piston and a connection between said valve and said piston. 80

4. A housing having an outlet in the bottom thereof and an inlet, said housing having therein above the outlet a cylindrical chamber open on the end toward said outlet and larger in diameter than said outlet, a piston in said chamber, an outwardly-opening valve for said outlet, said valve having a surface exposed to pressure in the chamber of smaller area than the area of said piston and a connection between said piston and said valve including a spring 95 under an initial tension acting in the direction tending to prevent the valve and the piston from being moved away from each other. 100

5. A housing having an inlet and an outlet, there being in the housing a cylindrical chamber open on the side toward said outlet and of larger cross sectional area than the outlet, a piston slidably mounted in said chamber, an outwardly-opening valve for said outlet, said valve having a surface exposed to pressure in the chamber of smaller area than the area of said piston and a connection between said valve and said piston, the parts being so constructed and arranged 110 that the valve and piston tend constantly to move in the direction to cause said outlet to be opened. 115

6. A housing having an inlet and an outlet, there being in the housing a cylindrical chamber open on the side toward said outlet and of larger cross sectional area than the outlet, a piston slidably mounted in said chamber, an outwardly-opening valve for said outlet, said valve having a surface exposed to pressure in the chamber of smaller area than the area of said piston, a connection between said valve and said piston permitting limited relative movements between the same from and toward each other, and 120 125 130

a spring under an initial tension forming part of said connection and tending constantly to hold said valve and said piston at the innermost limit of their relative movements.

7. A housing having an outlet in the bottom thereof and an inlet, said housing having therein above said outlet an open-bottom chamber of larger cross sectional area than 10 said outlet, a piston fitting slidably in said chamber, a downwardly-opening valve for said outlet, said valve having a surface exposed to pressure in the chamber of smaller area than the area of said piston, said valve 15 having a stem projecting upwardly through said piston, a shoulder on the upper end of said rod, and a spring under an initial ten-

sion arranged between said shoulder and the underlying portion of the piston.

8. A housing having an outlet in the bottom thereof and an inlet, a downwardly-opening valve for said outlet, a piston mounted in said housing and adapted to be moved upwardly by pressure in the latter, a yieldable connection between said valve 25 and said piston constructed and arranged to permit them to move away from each other when forces of predetermined strength are applied thereto, and means for admitting fluid under pressure above said piston to 30 cause it to travel down and open said valve.

In testimony whereof I sign this specification.

MORRIS B. BREWSTER.
